UNITED STATES PATENT OFFICE

FRANCIS WALTER GUIBERT, OF DETROIT, MICHIGAN

MECHANICAL TREATMENT OF STEEL

Application filed March 18, 1927. Serial No. 176,365.

This invention relates to the mechanical treatment of steel, and has to do particularly with a novel method and apparatus for working or rolling hot, as well as cold iron or steel, or alloyed steel.

Heretofore in the working of ferrous metals, either shortly after solidification in the ingot, or after cooling and reheating to working temperatures, it has been the practice to forge, roll or press the hot metal with steel rolls, or dies. Steel, or steel coated dies and rolls, or other forming elements, always have a certain affinity for the hot steel being rolled or forged, with the result that the rolled stock has a tendency to stick to the dies, or rolls, and produce a dull, unpolished appearance. It is well known in the art that the forging and rolling of hot steel by steel rolls, steel forging dies, etc., causes a certain amount of sticking, and the subsequent tearing away of the metal from the rolls leaves a dull surface. This rolled stock later requires considerable rolling when cold, to produce a polished surface suitable for highly finished parts such as automobile body sheets, fenders, stock for nickel plating, etc.

The present invention relates to the working or rolling of steel by rolling or forging instrumentalities having a rolling or forging face which does not have an affinity for the ferrous metal. More specifically, in carrying out this invention, I preferably provide non-ferrous rolls and forming means, or non-ferrous coated rolls and forming means whereby the hot or cold iron or steel in any form may be worked by such non-ferrous surfaces having no affinity for the iron or steel being worked. By thus working the iron or steel by means having no affinity thereto, it is possible to prevent the adhesion to a great extent and the resulting dull surface appearance which has heretofore been present on all iron or steel worked by working faces having affinity for the iron or steel.

In the drawings:

Fig. 1 is a diagrammatical view of a pair of working rolls constructed in accordance with my invention, the working surface of the rolls comprising a hard bronze jacket, and

the interior member being preferably of steel and provided with water cooling conduits.

Fig. 2 is a diagrammatical view showing a modification of the application of my invention wherein the forming rolls are constructed entirely of non-ferrous metal and providing suitable cooling means.

The application of my invention is well illustrated by the two figures of the drawings, but it will be understood that such illustrations are diagrammatical only, and that my method and apparatus may be utilized in many different forms in the practical mechanical treatment, and particularly the working, of hot iron or steel.

In Fig. 1, I have illustrated a pair of plain forming rolls 1 and 2 suitably housed in a frame 3. The central portion or main mass of the rolls is preferably formed of a steel body, while the actual working surface of the rolls is formed by suitable jackets 4 and 5 of a material for which iron or steel has little or no affinity, which fit around the steel rolls. As shown, these jackets 4 and 5 are held in position by means of the nuts 6 and 7 which may be fitted in any practical manner and are formed of a non-ferrous material, preferably bronze, or any material for which iron or steel has little or no affinity.

The steel rolls 1 and 2 may be hollow or contain suitable grooves 8 at or near the periphery, whereby a supply of cooling water can be had. The method and design of the cooling apparatus may be altered to fit different conditions arising and according to the thickness of the jackets, etc.

By thus providing a forming roll having a non-ferrous working surface, it will be seen that I may effect the working and particularly the working of hot steel in any desired form and thus obviate the defects usually resulting from the working of different steels where the working surfaces have an affinity for the material being worked. The non-ferrous working surfaces having little or no affinity for the steel being worked, it will be seen that the steel will pass between the rolls and come thru without the usual adhesion causing the dull finish. In working cold steel, it will reduce the num-

ber of passes required to give a polish, as against the use of steel or ferrous working faces. Obviously the cooling of the non-ferrous face, jacket, ring or cylinder, will greatly lengthen its life and efficiency.

In Fig. 2, I have illustrated a modified apparatus for carrying out my invention wherein the rolls 8 and 9 are formed themselves of a non-ferrous material. In the particular illustration I have also shown conduits 10 and 11 provided axially of the rolls for circulating cooling fluid therethrough. In the particular illustration, I have shown a pair of rolls for rolling sheet or bar stock, but it will be understood that such non-ferrous material may be utilized as the working or forming elements in any desired type of apparatus for mechanically working iron, steel or other ferrous metals. The point being that iron or steel may be reduced and formed without in any way causing any detrimental results in the surface due to the affinity between the working surfaces of the forming means and the iron or steel being formed and worked, but rather to improve that surface by filling in all the depressions, or rolling down the high points and producing a much more polished condition without the adhesion to the rolls caused by the pressure on and the affinity of the material being formed or rolled.

I am aware that attempts have been made to electro-plate rolls with nickel to prevent the forming of cracks in the rolls, but so far as I am aware I believe I am the first to mechanically treat or work iron or steel by means of working surfaces having no affinity for the iron or steel being worked whereby to produce strips, bars, sheets, etc., with a polished surface unmarred by the sticking to the working or rolling elements.

What I claim is:

1. The method of rolling ferrous metals, which comprises rolling and forming such ferrous metals by relatively moving rolling surfaces which have no inherent affinity regardless of their degree of polish for the ferrous metals being worked.

2. The method of rolling ferrous metals, which consists in bringing such metals to a temperature sufficient for rolling, and rolling and forming such hot metal by surfaces of non-ferrous material having little or no inherent affinity for the hot metal even when such surfaces are not smooth.

3. Apparatus for mechanically treating iron and steel and alloy steel, comprising a plurality of rolls positioned and spaced to work and form such metal, said rolls each comprising a jacket or jackets formed entirely of a non-ferrous material over a mandrel formed of ferrous material, said non-ferrous material having no affinity for the metal to be treated even when the surface of said jacket is not smooth.

4. Apparatus for mechanically treating iron, steel and alloy steels, comprising one or more rolls for working such metal, said rolls consisting of iron or steel over which cylinders revolve in co-ordination, said cylinders formed of a properly tempered material which has little or no affinity for iron, steel and alloy steels regardless of the degree of smoothness of said tempered material.

5. Apparatus for mechanically treating ferrous metals, comprising relatively movable working surfaces for receiving and working said metals, said working surfaces being formed of a bronze material having little or no affinity for the metal being worked.

In testimony whereof I affix my signature:

FRANCIS WALTER GUIBERT.
